UNITED STATES PATENT OFFICE.

WILLIAM AITKEN, OF LONDON, ENGLAND, ASSIGNOR TO THE RELAY AUTOMATIC
TELEPHONE COMPANY, LIMITED, OF LONDON, ENGLAND.

SYSTEM OF MULTIPLYING TRUNK-WIRES.

1,311,432.

Specification of Letters Patent.

Patented July 29, 1919.

Application filed March 20, 1917. Serial No. 156,069.

To all whom it may concern:

Be it known that I, WILLIAM AITKEN, a subject of the King of Great Britain, and resident of Marconi House, Strand, London, England, have invented a new and useful System of Multipling Trunk-Wires, of which the following is a specification.

This invention relates to a method of multiplying trunk or junction lines and the like over banks of switches or over relays so as to increase the access from incoming lines, and it is particularly applicable to automatic and semi-automatic telephone systems.

The invention will be described more particularly in connection with a relay system, as its application thereto is particularly beneficial, although it is applicable to any system and at pre-digit and digit stages and the like, and may be associated with jacks on semi-automatic systems.

In the usual way a number of trunks sufficient to carry the traffic is multiplied over the banks of switches or contacts of relays appertaining to a group of incoming lines, for example, ten trunks to one hundred subscribers.

In a relay system each subscriber's line would be equipped with ten relays, or a combination of relays to give access to ten lines, and subsidiary means would cause a calling line to select and connect with an idle line.

The object of the invention is to reduce the number of bank contacts or relays necessary to obtain the required access; or to enable groups of switches having a given number of terminals in a bank to have access to a greater number of lines. This invention is particularly applicable in the case of exchanges having groups of lines of more than two hundred in number. It is also, however, applicable to cases in which there are fewer lines than two hundred in a group, but the benefits to be derived from it in these cases of smaller groups are not so great as in the case of larger groups because they may be partially attained by other means.

The benefits accruing from the invention will be best realized if a group of 1000 lines will be considered.

At the pre-digit or line switch stage, it is usual to divide such a group into sub-groups of 100 lines each having access to 10 trunks, a total of 100 trunks. If 1000 subscribers

had access to one common group of trunks, only about 54 trunks would be required for a corresponding calling rate. This invention approximates to the latter condition by a novel way of multiplying the trunk lines, and at the same time reduces the number of bank terminals or relays necessary. The number of terminals or relays will vary according to traffic requirements.

According to this invention I multiple a group of trunks over each incoming line of a group so that each incoming line has access to a different combination of trunks, or I divide the subscribers' lines into very small sub-groups, say 2 to 4 in each, and I multiple the group of trunks over the sub-groups so that each sub-group has access to a different combination of trunks. In some cases it may be that different lines or sub-groups of the 1000 lines have access to two or possibly three similar trunks, but my particular arrangement of trunks reduces this to the minimum. The number of trunks in each combination will depend upon the requirements.

My invention so improves the access of incoming lines to outgoing trunks, and so automatically and efficiently distributes the traffic that secondary pre-selectors are unnecessary, primary pre-selectors can be of smaller capacity than formerly; no intermediate distributing board is necessary to equalize the traffic, and the number of trunks in a group can be increased to meet traffic growth as required without interference with the existing wiring. Adjacent lines have access to different combinations of trunks, which is particularly valuable on private branch exchange working.

My invention is also applicable to incoming calls, the incoming trunks being multiplied in a manner similar to the outgoing.

The invention is also applicable to the digit stages where preferably the incoming lines are divided into small sub-groups having access to different combinations of a group of outgoing lines.

I do not limit my invention to the applications specified, as it will be readily understood that it is applicable to any group of lines having access to another group of lines in telephony, telegraphy or any other art.

In order that my invention may be the

more readily understood I will now describe it with reference to the accompanying illustrative drawings and other features of my invention will be set out in the claiming clauses.

Figure 1 illustrates its application when each incoming line has access to a plurality of outgoing lines.

Fig. 1^a illustrates the application of the invention to a small installation so as better to illustrate the outstanding features by the use of a small number of lines.

Fig. 2 shows its application to sub-groups of incoming lines having access by links to a plurality of outgoing lines.

Fig. 3 shows its application to trunks wired to jacks on a manual telephone switchboard.

Fig. 1^a illustrates diagrammatically a 25-line switchboard with subscribers' lines 0 to 24, having access to a group of 18 outgoing trunks, capable of being increased to 24 trunks. Such a number of trunks is capable of serving a much larger number of subscribers than that specified, but 25 are sufficient to illustrate the application of the invention.

The group of outgoing trunks is divided into 5 sub-groups v^1 and v^5 .

Sub-group v^1 contains 7 trunks Nos. T1 to T7, and these are multiplied over the subscribers' lines as many times as 7 goes into the total subscribers' lines. It will thus be seen that the 7 trunks are multiplied over the subscribers' lines 0 to 6 inclusive, then 7 to 13 inclusive, 14 to 20 inclusive, and so on.

Sub-group v^2 contains 5 trunks, Nos. T8 to T12, and they are multiplied in a similar manner so that the 5 trunks are repeated on subscribers' lines 0 to 4 inclusive, 5 to 9 inclusive, 10 to 14 inclusive and so on.

Sub-group v^3 contains in the first instance 3 trunks, Nos. T13 to T15, multiplied in a similar manner. Alternate sets of 3 subscribers' lines are served by multiples in separate cables, the two cables in the first instance being connected by bridle wires a , b , c , so that they form a complete multiple of 3 trunks.

Sub-group v^4 contains 2 trunks Nos. T16 and T17 which are wired by 2 cables in the manner just described so that there is one complete multiple repeated for every 2 subscribers' lines.

Sub-group v^5 contains one trunk No. T18 which is wired by 2 parallel cables as before, so that all the 25 subscribers' lines have access to this one trunk.

Each subscriber's line is connected by relay or wiper contacts in any well known manner; these contacts being indicated by j . It will thus be seen that each subscriber's line has access to an outgoing trunk in each sub-group v^1 to v^5 and that adjacent sub-

scribers' lines have access to a different combination of 5 outgoing trunks. The following schedule shows the trunks to which the first 10 subscribers' lines have access:

25 subscribers' lines to 18 trunks.

Line 0 has access to trunks 1, 8, 13, 16, 18.	70
Line 1 has access to trunks 2, 9, 14, 17, 18.	
Line 2 has access to trunks 3, 10, 15, 16, 18.	
Line 3 has access to trunks 4, 11, 13, 17, 18.	75
Line 4 has access to trunks 5, 12, 14, 16, 18.	
Line 5 has access to trunks 6, 8, 15, 17, 18.	
Line 6 has access to trunks 7, 9, 13, 16, 18.	
Line 7 has access to trunks 1, 10, 14, 17, 18.	
Line 8 has access to trunks 2, 11, 15, 16, 18.	80
Line 9 has access to trunks 3, 12, 13, 17, 18.	

When, owing to increase of traffic or to meet the requirements of additional lines added, it is necessary to increase the number of trunks, this can be readily done without interfering with the existing multiple wiring: for example, if in sub-group v^5 the bridle wire f were to be removed, and a new trunk 24 added as shown, alternate subscribers' lines will have access to a different trunk in this sub-group. If 2 additional trunks are necessary bridle wires d and e of sub-group v^4 are removed and trunks 22 and 23 added so that alternate pairs of subscribers' lines have access to different outgoing trunks in this sub-group.

If three additional trunks are required, then the bridle wires a , b and c in sub-group v^3 are removed and additional trunks 19, 20 and 21 are added so that alternate sub-groups of 3 subscribers have access to different trunks.

If all the bridle wires a to f are removed and new trunks added as described, then the 18 trunk lines of the original equipment are increased to 24.

These figures are given merely by way of example, and the access of the first 10 subscribers' lines with 24 trunks is shown in the following schedule:—

25 subscribers to 24 trunks.

Line 0 has access to trunks 1, 8, 13, 16, 18.	
Line 1 has access to trunks 2, 9, 14, 17, 24.	
Line 2 has access to trunks 3, 10, 15, 22, 18.	115
Line 3 has access to trunks 4, 11, 19, 23, 24.	
Line 4 has access to trunks 5, 12, 20, 16, 18.	
Line 5 has access to trunks 6, 8, 21, 17, 24.	
Line 6 has access to trunks 7, 9, 13, 22, 18.	
Line 7 has access to trunks 1, 10, 14, 23, 24.	120
Line 8 has access to trunks 2, 11, 15, 16, 18.	
Line 9 has access to trunks 3, 12, 19, 17, 24.	

Fig. 1 shows a similar arrangement applied to a larger equipment, for example, 1000 subscribers' lines having access to 60 trunks in the first instance, the trunks being capable of increase to 86. The intersections of lines at the points j indicate relay contacts which correspond to the contacts j in Fig. 1^a.

Each sub-group of outgoing junctions is indicated by a line representing a cable to avoid confusion owing to the greater number of lines in each sub-group.

5 In Fig. 1 the horizontal lines S , numbered 0 to 999, indicate subscribers' or other incoming lines; each having access by wipers or relay contacts j to five vertical lines v each of which represents a cable containing 10 a plurality of outgoing trunks. It is assumed that 60 outgoing trunks are sufficient to carry the traffic from the 1000 incoming lines, but any other requisite total may be used. The group of trunks is divided into 15 sub-groups v according to the access required and five are shown by way of example; five are believed to be sufficient when each incoming line has access to a different combination of trunks.

20 A different number of trunks is preferably allotted to each sub-group, and preferably such number is a prime. One exception to this is shown, the number of trunks in the five sub-groups being 17, 14, 13, 11, 5, total 25 60. To allow for traffic growth the sub-group of 11 is shown with two cables m , m , each wired to alternate multiples, the two cables being connected in parallel at a joint board to 11 trunks. Sub-group 5 is shown 30 wired by four cables e , f , g , h , each serving different multiples of 4 sections. These are all connected in parallel at the joint board to a set of 5 trunks. The other sub-groups are wired by single multiplied cables.

35 To meet traffic increase, the sub-group of 5 may be increased to 10 by breaking the bridle wires a^1 , b^1 , c^1 , and connecting e , g , and f , h , to put the four cables in sets of pairs in parallel serving alternate multiples 40 by trunks e' , g' . The trunk multiple numbers 56 to 60 on cable f will then be replaced by numbers 61 to 65. To increase further by 6, the two cables of sub-group 11 are separated at d and 11 trunks n' are connected to the separated cable n , thus increasing the multiple capacity to 22. The trunk multiple numbers 45—55 on cable n will thus be replaced by numbers 76—86. The right hand sub-group should then be reduced 45 again to 5 with 4 cables in parallel. To increase further by 5, open out again the 5 sub-group to two pairs of cables in parallel.

To increase further by 10, open out the 5 (10) sub-group, and increase the trunks 55 in that sub-group to 20 by connecting trunks f' and h' . The trunk multiple of cable e will then be numbers 56—60, cable f numbers 61—65, cable g numbers 66—70 and cable h numbers 71—75. The group has thus been 60 increased from 60 by 5, 6, 5, 10, to a total of 86 trunks without interfering with the existing wiring.

The incoming lines may be worked in one group up to 10,000 lines, the increase in 65 number always bringing about increased

efficiency and a percentage decrease in the number of outgoing trunks owing to the efficiency of large groups.

In such larger groups a decrease in the number of incoming lines having access to a 70 plurality of similar outgoing lines occurs, until at a certain point no access to a similar plurality exists.

By way of example, to increase to 2000 lines or over all sub-groups would be wired 75 by a plurality of cables with the following result:

For 1000 lines 17, 14, 13, 11, 5=60 outgoing trunks.

For 2000 lines 34, 28, 26, 22, 10=120 outgoing trunks.

For traffic growth 44, 20=158 outgoing trunks.

The different sub-groups are doubled as required, and the ultimate may be utilized 85 for a 3000 line group at one calling rate, and for 2000 lines on a higher calling rate.

It will be found that the incoming line having a number which corresponds with the product of any two sub-group numbers 90 will have access to two trunks in common with one or more other lines; for example, in a 60 trunk group, subscriber 55 (11x5) will have access to trunks in sub-groups 11 and 5 in common with No. 0 and every multiple 95 of 55, and subscriber 238 (17x14) will have access to a 17 and 14 sub-group in common with No. 0 and multiples of 238. At the product of any 3 sub-group numbers an incoming line will have access to three trunks 100 similar to No. 0; for example, Nos. 0 and 715 (13x11x5) have access to the same trunks in sub-groups 13, 11 and 5; subscribers 0 and 770 have access to three similar trunks in 14, 11 and 5; and 0 and 910 105 access to 3 similar trunks in 14, 13 and 5. Other multiples and combinations are beyond the 1000 line multiple, and there are never more than two subscribers having access to the same three trunks in a combination, and no two subscribers have access to the same trunks in the 17 and 14 groups.

It will be obvious from the mathematical formula for the number of combinations of n things r at a time, that as the number of 115 trunks increases, this common access is decreased, until in the example of a 10,000 line exchange with 597 trunks as described below there would be no common access to a plurality of similar outgoing trunks.

A 2000 line pre-selector unit having 107 trunks can be increased to 5000 (or other number according to the traffic) with 262 trunks:

Original equipment 2000 lines having access to 125 31, 29, 23, 13, 11=107.

Increased to 5000 lines having access to 62, 58, 46, 26, 22=214.

Allowance for increased traffic growth 52, 130 44=262.

Similarly 10,000 subscribers' lines may be connected in one group to 449 trunks, increasing by steps to 597 trunks to meet increased calling rate:—

5 10,000 line group:

127, 119, 113, 61, 29=449 trunks.

122, 58=539 trunks.

116=597 trunks.

10 For very small groups of incoming lines it is sometimes advantageous to reverse the trunks or otherwise to transpose them so that the trunks of a sub-group are in a different order in the repetitions of the multiple. Also in some circumstances it is advantageous to repeat the same trunks in a plurality of sub-groups or levels. For example, in a group of 60 trunks divided into 5 sub-groups, 35 trunks may be multiplied 15 as a first sub-group or level, 31 (Nos. 5 to 35) multiplied as a second level, 36 to 44 plus 1 to 4, total 13, multiplied as a third level, 11 and 5 as fourth and fifth levels (arranged as before for increasing the total 20 lines in group), total 60. If a greater increase is required than can be given in the last two levels, new trunks can replace 1 to 4 on the third level, and a new set of trunks 25 replace 5 to 35 on the second level.

30 The arrangement has been described for adjacent individual incoming lines having access to different trunks, but when traffic is light and for small exchanges a plurality of adjacent incoming lines may have access to 35 the same trunks and combinations of this arrangement may be used. For example, adjacent individual incoming lines may each have access to a different trunk on the first 40 sub-group of outgoing trunks, pairs of adjacent incoming lines may have access to each outgoing trunk of the second sub-group, three adjacent incoming lines may have access to the same outgoing trunk of the third sub-group, and so on, the outgoing 45 sub-groups of outgoing trunks being multiplied as before described.

Fig. 2 shows my invention adapted to work with incoming lines IL, which may be subscribers' or trunk lines, arranged in small 50 sub-groups which connect with the trunks by links LK, and used at a pre-selector or at a digit switching stage. Three incoming lines are shown connecting by wipers, relays and the like to 5 or other number of 55 links LK, which in turn connect by similar means with a set of 5 (one in each sub-group v^1 to v^5) or other number of outgoing trunks T in 1G, 2G. Each link has access to all the groups G of (for example) 60 1000 lines. The outgoing lines are sub-divided and multiplied as before described.

Fig. 3 shows the sub-groups of outgoing trunks multiplied to jacks j . One or a plurality of sets (j^1 to j^s being a set), would be 65 fitted in front of each operator who would

be provided with the usual connecting means to extend one of a group of calling lines to a trunk line.

I have shown the largest division of sub-groups as first choice lines and the smaller as subsequent and final choice lines. I may, however, especially in semi-automatic systems and to obtain concentration of traffic, reverse this arrangement, making the smallest sub-group first choice and the larger sub-groups subsequent choice lines. 75

What I claim is:—

1. The combination of a group of lines and a smaller group of lines to which the first lines have access and which is divided into sub-groups, the number of sub-groups being equal to the number of lines to which each line of the first group is to have access and each sub-group containing a different number of lines. 80

2. The combination of a group of lines and a smaller group of lines to which the first lines have access and which is divided into sub-groups, the number of sub-groups being equal to the number of lines to which each line of the first group is to have access and each of a plurality of sub-groups containing a different number of lines. 85

3. The combination of a group of lines and a smaller group of lines to which the first lines have access and which is divided into sub-groups so that the number of lines in a sub-group can be increased in number without affecting the wiring of the sub-group. 90

4. The combination of a group of lines and a smaller group of lines to which the first lines have access and which is divided into sub-groups, the number of sub-groups being equal to the number of lines to which each line of the first group is to have access, each sub-group containing a different number of lines and the lines of each sub-group being multiplied as many times as the number of lines of such sub-group goes into the 105 number of lines of the first group. 110

5. The combination of a group of lines and a smaller group of lines to which the first lines have access and which is divided into sub-groups, the number of sub-groups being equal to the number of lines to which each line of the first group is to have access, each of a plurality of sub-groups containing a different number of lines and the lines of each sub-group being multiplied as many times as the number of lines of such sub-group goes into the number of lines of the first group. 115

6. The combination of a group of lines and a smaller group of lines to which the first lines have access and which is divided into sub-groups so that the number of lines in a sub-group can be increased in number without affecting the wiring of the sub-group and in which the lines of each sub- 120 125 130

group are multiplied as many times as the number of lines of such sub-group goes into the number of lines of the first group.

7. The combination of a group of lines and a smaller group of lines to which the first lines have access and which is divided

5 into sub-groups, the number of sub-groups being equal to the number of lines to which each line of the first group is to have access,

10 each sub-group containing a different number of lines and the lines of a sub-group being multiplied as many times as the number of lines of that sub-group goes into the number of lines of the first group.

15 8. The combination of a group of lines and a smaller group of lines to which the first lines have access and which is divided into sub-groups, the number of sub-groups being equal to the number of lines to which

20 each line of the first group is to have access, each of a plurality of sub-groups containing a different number of lines and the lines of a sub-group being multiplied as many times as the number of lines of that sub-group goes into the number of lines of the first group.

25 9. The combination of a group of lines and a smaller group of lines to which the first lines have access and which is divided into sub-groups so that the number of lines 30 in a sub-group can be increased in number without affecting the wiring of a sub-group and in which the lines of a sub-group are multiplied as many times as the number of lines of that sub-group goes into the number 35 of lines of the first group.

30 10. The combination of a group of lines and a smaller group of lines to which the first lines have access and which is divided into sub-groups, the number of sub-groups 40 being equal to the number of lines to which each line of the first group is to have access, the lines of each sub-group being multiplied as many times as the number of lines of such sub-group goes into the number of lines of 45 the first group and the lines of a sub-group being in different numerical orders in the repetitions of the multiple.

45 11. The combination of a group of lines and a smaller group of lines to which the first lines have access and which is divided 50 into sub-groups, the number of sub-groups being equal to the number of lines to which each line of the first group is to have access, the lines of each sub-group being multiplied 55 as many times as the number of lines of such sub-group goes into the number of lines of the first group and the lines of a sub-group starting from a different numerical base in repetitions of the multiple.

60 12. The combination of a group of lines and a smaller group of lines to which the first lines have access and which is divided into sub-groups, the number of sub-groups being equal to the number of lines to which 65 each line of the first group is to have ac-

cess, the lines of a sub-group being multiplied as many times as the number of lines of that sub-group goes into the number of lines of the first group and the lines of a sub-group being in different numerical 70 orders in the repetitions of the multiple.

13. The combination of a group of lines and a smaller group of lines to which the first lines have access and which is divided into sub-groups, the number of sub-groups 75 being equal to the number of lines to which each line of the first group is to have access, the lines of a sub-group being multiplied as many times as the number of lines of that sub-group goes into the number of lines of 80 the first group and the lines of a sub-group starting from a different numerical base in repetitions of the multiple.

14. The combination of a group of lines and a smaller group of lines to which the 85 first lines have access and which is divided into sub-groups, the number of sub-groups being equal to the number of lines to which each line of the first group is to have access, the lines of each sub-group being multiplied 90 as many times as the number of lines of such sub-group goes into the number of lines of the first group and the number of sub-groups of incoming lines having access to sub-groups of outgoing lines varying in different 95 sub-groups of outgoing lines.

15. The combination of a group of lines and a smaller group of lines to which the first lines have access and which is divided into sub-groups so that the number of lines 100 in a sub-group can be increased in number without affecting the wiring of the sub-group, one of the sub-groups having its multiple wired by a plurality of cables.

16. The combination of a group of lines, 105 a smaller group of lines to which the first lines have access and which is divided into sub-groups, the number of sub-groups being equal to the number of lines to which each line of the first group is to have access, a group of trunk lines and a plurality of cables serving the multiple of a sub-group and connected in parallel to a group of trunk lines equaling in number the circuits in one cable.

115 17. The combination of a group of lines, a smaller group of lines to which the first lines have access and which is divided into sub-groups, the number of sub-groups being equal to the number of lines to which each line of the first group is to have access, a group of trunk lines and a plurality of cables serving the multiples of a plurality 120 of sub-groups and each connected in parallel to a group of trunk lines equaling in number the circuits in one cable.

18. The combination of a group of incoming lines and a group of outgoing trunk lines, each incoming line having access to a different combination of outgoing trunks, 130

and never more than two incoming lines having access to the same three trunks of the possible accessibility.

19. The combination of a group of incoming lines and a group of outgoing trunk lines, each incoming line having access to a different combination of outgoing trunks, and no incoming line having access to more than two lines in common with other lines.

10 20. The combination of a group of incoming lines and a group of outgoing trunk lines, each incoming line having access to a different combination of outgoing trunks,

and no pair of trunks being used in common by any pair of incoming lines.

21. The combination of a group of incoming lines divided into sub-groups, a group of outgoing lines and links by which the sub-groups have access to the outgoing lines and which are divided into sets, each set having access to a different combination of outgoing lines.

In testimony that I claim the foregoing as my invention, I have signed my name this 28th day of February 1917.

WILLIAM AITKEN.
